[57] CLAIM

The ornamental design for a hanger clip, as shown and described.

DESCRIPTION

FIG. 1 is a top, front, right side perspective view of a hanger clip showing my new design; the broken lines indicating a flanged T-member for a suspended ceiling are shown for illustrative purposes only and forms no part of the claimed design;

FIG. 2 is a front elevational view of the right clip half, the left half being substantially a mirror image;

FIG. 3 is a rear elevational view of the right clip half, the left half being substantially a mirror image;

FIG. 4 is a left side elevational view of the right clip half, the left half being substantially a mirror image;

FIG. 5 is a right side elevational view of the right clip half, the left being substantially a mirror image;

FIG. 6 is a front elevational view of a clip;

FIG. 7 is a top plan view of the clip; and

FIG. 8 is a bottom plan view of the clip.
